UNITED STATES PATENT OFFICE.

WILLIAM F. LAING, OF CUMBERLAND, MARYLAND.

POISON BOTTLE.

Application filed February 10, 1920. Serial No. 357,644.

To all whom it may concern:

Be it known that I, WILLIAM F. LAING, a citizen of the United States, residing at Cumberland, in the county of Allegany and State of Maryland, have invented certain new and useful Improvements in Poison Bottles; and I do hereby declare the following to be a full, clear, and exact description of the invention, such as will enable others skilled in the art to which it appertains to make and use the same.

This invention relates to an improved container for poisons said poison being in the form of liquid, pills, powder or other form usually stored in bottles or the like and may be briefly termed a poison bottle.

An object in view is to provide a receptacle for poison, having an outward appearance similar to bottles containing harmless substances, to permit its general use for instance in drug stores where uniformity is desired and the bottles are arranged in rows on shelves, some containing poison and others harmless substances.

Provision is also made for the use of said poison bottles on the same shelves with bottles containing harmless substances, the latter having labels closely resembling those on the poison bottles, without any danger 30 of a serious mistake by a clerk in hastily making up a prescription.

Another object is to provide a poison receptacle of special value in homes where there are small children who soon learn to draw a cork out of a bottle, by concealing or placing the discharge opening at a point remote from its usual location, by providing a false cork in the place usually occupied by the stopper, which if drawn by a child without result, would ordinarily cause him to discontinue his efforts to remove the contents of the bottle, and also by providing a stopper that is preferably screwed into place and is therefore removed in a 45 manner different from that of the ordinary stopper.

A further object is to provide a safety container of such a character that accidents may be avoided which might be caused by 50 picking up the wrong bottle in the dark, for instance in emergencies at night, when the selection of a bottle is made from its size and outline only.

These and other objects are obtained by 55 providing a bottle adapted for use as a container for poison, requiring an opera-

tion when withdrawing its contents, that is wisely different and if necessary more difficult, than that required for the withdrawal of the contents of the ordinary form of 60 bottle, thereby indicating and forcibly impressing on the mind of the person using the bottle that he is handling a poison.

This invention consists of such novel features of construction and arrangement of 65 parts as will be hereinafter more fully described, illustrated in the accompanying drawings and finally claimed.

Reference will be had to the drawings wherein like characters designate corresponding parts throughout the views, in which:

Figure 1 is a vertical section of the improved poison bottle, taken centrally through the outlet port, showing the stopper 75 and false cork in elevation.

Figure 2 is a section on line 2—2 of Figure 1 looking in the direction of the arrow,

Figure 3 is a vertical section similar to Figure 1 of the lower portion of the bottle 80 showing a slightly modified form thereof.

Referring to the drawing more particularly, 1 designates the body of the container which may be of any preferred form and material but for the purpose of illustration 85 is shown similar to the ordinary glass bottle having a neck 2.

The neck 2 and in fact the container throughout may be made to resemble any preferred form of bottle, as viewed when 90 resting in its normal position on a shelf or other similar support.

The neck 2 is however provided with a false or blind discharge opening 3, in which is seated the false cork 4. The opening 3 95 does not communicate with the interior of the bottle but simply receives the cork which gives the upper part of the bottle its usual normal appearance.

The bottom 4 is preferably slightly above 100 the base of the bottle to provide an elongated threaded discharge opening for the reception of a correspondingly threaded stopper 5. The discharge opening 6 is formed between the side wall of the bottle and the 105 flange 7 depending from the bottom 4 of the bottle.

The stopper 5 may be glass or any other suitable material but is preferably of cork, provided with threads of only slight depth 110 to insure against accidental displacement but requiring a rotary movement for its re-

moval. Any preferred means may be provided for the removal of the stopper 5 such as a knob 8 or the like permanently mounted therein, which may be grasped to rotate 5 the stopper, or temporary means such as a cork screw may be inserted to accomplish the desired result.

When the poison bottle is used as a receptacle for liquid the stopper is preferably 10 located as near one side of the bottle as is possible and to further facilitate pouring, the outer edge of the discharge opening 6 may be cut away to provide a pouring lip shown at 9.

15 When used as a receptacle for dry substances such as powder, pills or the like, a slightly modified form of bottle may be used as shown in Figure 3 in which the discharge opening 10 is centrally located.

20 The benefits of a receptacle of this character will be obvious, it being clear that while the bottle as above described will have all the outward appearances of other bottles and possess all the benefits of same, its peculiar construction will effectively prevent 25 any mistakes due to any confusion between same.

One of the principal features of merits in the construction shown, is that a person who 30 through mistake attempts to withdraw the

contents of this poison bottle, thinking he has another bottle of a harmless character is permitted to go to such an extent towards procuring the poison that when he finally realizes his mistake, he will receive 35 a sufficient shock to deeply impress him. He not only selects the bottle but he withdraws the cork and tilts the bottle to discharge its contents before he realizes his mistake and what might have been the result of his carelessness. 40

What is claimed is:

A bottle having the usual neck which is permanently sealed at its inner end and having 45 a raised bottom with the side projecting some distance therebelow, the bottom having a discharge opening therein adjacent a depending portion of the side, which latter forms a pouring lip, and a flange in line with the discharge opening and acting with the depending portion of the side forming the pouring lip to provide for the reception of a stopper.

In testimony whereof I affix my signature in presence of two witnesses.

WILLIAM F. LAING.
